Primary Examiner — Eric L Goodman*Assistant Examiner* — Clare A Gannon(74) *Attorney, Agent, or Firm* — Gardner, Linn, Burkhardt & Ondersma LLP(57) **CLAIM**

The ornamental design for a roller window blind hook, as shown and described.

DESCRIPTION

FIG. 1 is a perspective view of a roller window blind hook showing my new design;

FIG. 2 is an end elevation thereof;

FIG. 3 is a front elevation thereof;

FIG. 4 is a rear elevation thereof;

FIG. 5 is a top plan view thereof;

FIG. 6 is a bottom plan view thereof;

FIG. 7 is another front perspective view of the roller window blind hook of FIG. 1, with a roller blind tube and blind panel shown as environmental structure;

FIG. 8 is a perspective view of another roller window blind hook showing my new design;

FIG. 9 is an end elevation view thereof;

FIG. 10 is a front elevation thereof;

FIG. 11 is a rear elevation thereof;

FIG. 12 is a top plan view thereof;

FIG. 13 is a bottom plan view thereof; and,

FIG. 14 is another front perspective view of the roller window blind hook of FIG. 8, with a roller blind tube and blind panel shown as environmental structure.

In the drawings, the broken lines depict portions of the roller window blind hook and environmental structure that form no part of the claimed design.

In the drawings, portions of the roller window blind hook between the break lines and designated by brackets in FIGS. 1, 3-8 and 10-14 form no part of the claimed design.
